PCT/US2016/017918 Search Report and Written Opinion dated May 3, 2016.

Primary Examiner — Karen E Kearney*Assistant Examiner* — Michael Chong(74) *Attorney, Agent, or Firm* — Boardman & Clark LLP(57) **CLAIM**

The ornamental design for a battery module connector barrel, as shown and described herein.

DESCRIPTION

FIG. 1 is a front overhead perspective view of a connector barrel showing our new design;

FIG. 2 is a back overhead perspective view thereof;

FIG. 3 is a top plan view thereof;

FIG. 4 is a bottom plan view thereof;

FIG. 5 is a right side elevation view thereof;

FIG. 6 is a left side elevation view thereof;

FIG. 7 is a front elevation view thereof; and,

FIG. 8 is a back elevation view thereof.

The broken line showing of a battery module connector barrel is for the purpose of illustrating portions of the article and forms no part of the claimed design.
